CLAIM

The ornamental design for a programmable logic controller system module, as shown and described.

DESCRIPTION

This application is related to the following co-pending applications: U.S. Ser. No. 29/292,016, filed Sep. 25, 2007 and titled “Programmable Logic Controller System Module”; U.S. Ser. No. 29/292,015, filed Sep. 25, 2007 and titled “Programmable Logic Controller System Module”; U.S. Ser. No. 29/292,017, filed Sep. 25, 2007 and titled “Programmable Logic Controller System Module”; and U.S. Ser. No. 29/292,019, filed Sep. 25, 2007 and titled “Programmable Logic Controller System Module”.

FIG. 1 is a top, front, left side perspective view of a first embodiment of a programmable logic controller system module showing our new design;

FIG. 2 is a front view thereof, the back view being a mirror image;

FIG. 3 is a left side view thereof, the right side view being a mirror image; and,

FIG. 4 is a top view thereof.

The “dash-dot-dash” broken lines defines the bounds of the claimed design and form no part thereof. The portions of the programmable logic controller system module shown in evenly-spaced broken lines form no part of the claimed design.
